UNITED STATES PATENT OFFICE

100,581

DESIGN FOR A SHOE

Aaron Runstein, Jersey City, N. J.

Application June 8, 1936, Serial No. 63,103

Term of patent 3½ years

To all whom it may concern:

Be it known that I, Aaron Runstein, a citizen of the United States, residing at Jersey City, county of Hudson, State of New Jersey, have invented a new, original, and ornamental Design for Shoes, of which the following is a specification, reference being had to the accompanying drawing, forming part thereof.

The figure is a perspective view of a shoe, showing my new design.

I claim:

The ornamental design for a shoe as shown.

Signed at New York, in the county of New York, and State of New York, this 6th day of June, 1936.

AARON RUNSTEIN.
